UNITED STATES PATENT OFFICE.

AUGUSTUS J. GOFFE AND DEMUS GOFFE, OF COHOES, NEW YORK, ASSIGNORS TO DOWNS & CO., OF SENECA FALLS, NEW YORK.

KNITTING-MACHINE.

Specification of Letters Patent No. 26,231, dated November 22, 1859.

To all whom it may concern:

Be it known that we, AUGUSTUS J. GOFFE and DEMUS GOFFE, of Cohoes, in the county of Albany and State of New York, have 5 jointly invented certain new and useful Improvements on the Knitting-Machine for which Letters Patent were granted to us bearing the date of August 5, 1856; and we do hereby declare that the following is a 10 full and exact description thereof, reference being had to the annexed drawings making part of this specification.

Figure 1, being a perspective view of a part of the revolving top plate A, a portion 15 thereof being removed to show the needles. Fig. 2, is an elevation of the rotary presser and yarn layer M. Fig. 3, is a section thereof. Fig. 4, is an elevation of a modification of the presser adapted to forming open and 20 ornamental work. Fig. 5, is an inverted view of a part of the revolving top plate, showing the variable antifriction cam for sliding the needles. Fig. 6, is an elevation of the friction brake for regulating the tension of the thread the standard of which is 25 broken, a part being shown in Fig. 1.

Similar letters refer to corresponding parts in all the figures.

Our improvements relate first to laying 30 the yarn and pressing the barb of the needle over it to insure its being drawn through the loop. Instead of employing for this purpose the stationary presser referred to by the letter D, in the drawings annexed to 35 our patent, we use a rotary bur or pinion, M, having teeth corresponding in size with the interstices between the needles at the point where it is applied, which, by gearing with them, as the top plate A, to which it is 40 pivoted, revolves, causes it to rotate and lay the thread so close the needles—(the teeth by pressing it between them securing close contact with their upper surfaces,) as to insure its being drawn under the barbs as 45 the needles are made to slide back by the eccentric groove.

The bottom of each space or groove between the teeth forms an inclined plane, as at a Fig. 3, which receives the barb of the 50 needles and causes it to spring or close down into the eye while it is being drawn through the loop or stitch.

The teeth of the bur-presser have a greater projection on one side, forming a

shoulder as at b Fig. 3, which serves to lay 55 the thread in the proper position on the needles and to hold it firmly while the barb is drawn over it. The advantages of this method of laying the thread and pressing it within the barb of the needles are obvious, 60 as acting with greater certainty, and accomplishing both the objects of laying the thread and bearing down the barbs at one operation, while it overcomes much friction which is inseparable from the stationary 65 presser, and thereby effects a saving both in the power required and the wear of the machine.

The bur-presser is capable of certain modifications which adapt it to producing a 70 species of ornamental knitting which may be varied at pleasure by altering the arrangement of the teeth. A method of accomplishing this is shown by omitting the inclined planes, or deep-grooving the spaces 75 in alternate pairs of the teeth as seen at c c Fig. 4. This produces openwork in the web wherever the inclined planes are omitted, as the space of two unformed stitches is left. By a proper arrangement of the teeth, and 80 the number of needles, viz.—using a number of needles that may be divided by four and leave two remaining in order to form and omit two stitches alternately, or for omitting one stitch alternately, a number 85 that will divide by two and leave one, the stitch-forming teeth will alternately take the position of the vacant teeth at each revolution, and thus produce an ornamental web, the design of which is capable of a great 90 variety of changes. A pleasing effect may be produced by using two or more pressers formed in this manner each with yarn of different colors, and one alternating the 95 stitches formed by the other.

A further improvement consists in constructing the groove, f, so as to be variable by means of the friction pulley g, and thumb screw h. By turning the thumb screw in one direction pulley g is drawn outward from 100 the center, and the eccentricity of the groove rendered greater and more acute, and vice versa. One side of the groove is formed by the slip of spring steel, k, which, by its pliability, adapts itself to the change of the 105 pulley, and thus keeps the wall of the groove perfect. The movable pulley, g takes off the friction at the point where it is greatest,

while, by drawing it out as described, the needles are drawn farther back from the loop-forming stops *c c*. These stops, as shown in Fig. 1, are formed by the inner periphery of the grooved annular top-plate, *A*, in which the needles work, and consist of those portions of the plate which intervene between the grooves for the needles. Their office is to hold the loop (or stitch) while the 10 barb of the needle, acted upon by the presser *M*, as previously described, is drawn through, so that said loop is dropped from the needle and becomes a part of the web. It will be borne in mind that the needle carries 15 the newly laid thread within its barb or hook, through the loop dropped off, thus forming another loop, and on the size or length of these loops depends the closeness of the web. Thus by turning the thumb-screws 20 *h* so as to draw the pulley *g* outward, and thereby make the eccentricity of the groove *f*, greater, the barb end of the needles is drawn farther back of or past the stops *c*, the effect of which is to increase the length 25 of the loops and make the web more loose and open. By adjusting the eccentricity of the groove in this manner the work may be enlarged or diminished as required, and when the yarn is uneven the knitting may

be so regulated as to keep the size of the web 30 uniform.

The pulley *l* is on a stationary axis and is employed to give easy motion to the needles as they pass the part of the groove at *m*, which has a curve of less radius introduced in order to cause the needles to act quickly at this point to insure the drawing of the barbs over the thread while it is held down by the presser.

What we claim as our invention is— 40

1. The rotary bur presser *M*, having inclined planes *a*, between the teeth, in combination with sliding needles, arranged and operating substantially in the manner and for the purpose shown and described. 45

2. We also claim varying the eccentricity of the groove *f* by means of the movable pulley *g*, spring *k*, adjusting screw *h*, and friction pulley *l*, substantially in the manner, and for the purposes herein described.
